United States Patent Office.

JAMES H. SWINDELL, OF CAMDEN, NEW JERSEY.

Letters Patent No. 77,126, dated April 21, 1868.

IMPROVEMENT IN INDEXING BOOKS AND LEDGERS.

The Schedule referred to in these Letters Patent and making part of the same.

TO ALL WHOM IT MAY CONCERN:

Be it known that I, JAMES H. SWINDELL, of Camden, in the county of Camden, and State of New Jersey, have invented a new and improved Method of Indexing Books, Ledgers, &c.; and I do hereby declare that the following is a full, clear, and exact description thereof, which will enable others skilled in the art to make and use the same, reference being had to the accompanying drawings, forming a part of this specification, in which—

Figures 1 and 2 represent face views of my invention.

Similar letters of reference indicate corresponding parts.

This invention relates to a new method of indexing books, ledgers, &c., so that with two or three turns any desired page can at once be found.

The invention consists in subdividing, by means of notches, such pages which are found by means of the ordinary notches, indicating the capital letters or the hundreds or thousands, as the case may be.

The invention is particularly applicable to large dictionaries, account-books, lexica, and other large books.

A A represent the notches cut into the margin of a lexicon or other book, D, to find the commencement of words or names which begin with certain capital letters.

These notches extend from the first page respectively to those pages at which such words commence, and at the bottom of each notch is printed upon the leaf forming the bottom the required capital letter. This arrangement of one set of notches is already in use in many books.

My invention consists in subdividing, by means of notches, the leaves for every particular letter.

Thus, in fig. 1, it is shown that the margin of the book is provided with notches B B, to each of which one or more letters are marked, such letter or letters indicating the second or third letter of the word, commencing with the capital letter in the department of which such notches B are arranged. Thus, for example, the commencement in the book of the words beginning with the capital letter E, having been found by the aid of the notches A, the notches B B on the first page, containing such letters which commence with the letter E, are marked by letters *g, g, l i, m p, &c.*, denoting that the leaf which forms the bottom of such notch contains the words commencing with the letters Egg, Eli, Emp, &c.

For very large books, the leaves between the notches B may be again subdivided by notches indicating still more letters of commencement than the notches B, and thus a required word can easily be found by two or three turns. For example, the word "Excelsior" is to be found. The commencement of the words beginning with the letter E is found by means of the notches A. The first page of E displays the notches B appended to the letter E, and thereby the words commencing with the letters Exc can be found at once.

If the book is very voluminous, a subdivision, by a third series of notches, may show the words commencing with the letters Excel. The arrangement of this subdivision may be varied. Thus the marks referring to the bottom page of each notch B may be on such bottom page at the bottom of each notch, or on the top page, near the margin of each notch, as in fig. 1.

The same device can be used for a numerical as well as for an alphabetical index, as shown in fig. 2, in which A' are the notches dividing the pages as to hundreds, and B' B' are notches subdividing the pages containing certain hundreds into tens. Those containing certain tens may again, by means of notches, be subdivided to indicate units, &c.

A small spatula or narrow plate, C, fig. 1, will be very convenient for finding the required page, the point of the instrument being inserted at the bottom of the required notch, when the book is easily opened at the desired place.

Having thus described my invention, what I claim as new, and desire to secure by Letters Patent, is—

Arranging an alphabetical or numerical index for books, by cutting two or more sets of notches in the margins of such books, and by making appropriate marks to each of the said notches, substantially as and for the purpose herein shown and described.

JAMES H. SWINDELL.
